UNITED STATES PATENT OFFICE.

MARTIN LÉONARD EDMOND DUVAL, OF PARIS, FRANCE, ASSIGNOR TO THE
SOCIÉTÉ ANONYME DITE COMPAGNIE DE FIVES-LILLE, OF SAME PLACE.

MECHANICAL DEVICE FOR SHUTTING THE DOORS OF DIFFUSING APPARATUS.

SPECIFICATION forming part of Letters Patent No. 369,845, dated September 13, 1887.

Application filed March 14, 1887. Serial No. 230,628. (No model.)

To all whom it may concern:

Be it known that I, MARTIN LÉONARD EDMOND DUVAL, a citizen of the Republic of France, residing at Paris, in said Republic, 5 have invented a new and useful Improvement in Mechanical Devices for Closing the Gates of Diffusing Apparatus, of which the following is a specification.

The object of this invention is to facilitate 10 the closing and fastening of the movable bottoms or discharge-gates of diffusing apparatus, and is especially applicable to cylindro-conical, cylindrical, and conical diffusers of great capacity for the treatment of beet-root, sugar- 15 cane, bagasse, and other matters.

The invention is illustrated in the accompanying drawings, in which Figures 1 and 2 are elevations at right angles to each other of a diffusing apparatus having my invention applied. Fig. 3 is a horizontal section, partly in the line *a b* and partly in the line *c d* of Fig. 1. Fig. 4 is a plan. Fig. 5 is a front view of the articulation of the discharge-gate and of the mechanism for opening and closing the same. 25 Fig. 6 shows a horizontal section in the line *e f* of Fig. 5, and Fig. 7 is a side view of the fastening mechanism.

Similar letters of reference designate corresponding parts in all the figures.

30 The movable bottom *P* of the diffuser, constituting the discharge-gate, is articulated at *X* at the middle of its height and furnished with a counterpoise, *A*, which has the effect of balancing the weight in all positions, and 35 therefore rendering the operation very easy. This operation is executed by means of four rods, *B B C C*, provided with crank-handles *D D*, and guided by stationary sockets *E*, cast with the upper part of the diffuser, and supported at their lower ends in sockets forming step-bearings cast with the lower part of the diffuser.

40 The opening mechanism, placed between the articulation *X* of the gate and the axis of the diffuser, is composed of the two rods *B B*, capable of turning freely in the sockets *E E*. Each of these rods is screw-threaded on its lower part, as shown at *F* in Figs. 1 and 5, and carries a nut which is capable of rising and 45 falling freely in a slideway, *M*, secured to the

diffuser. Upon this nut is articulated a connecting-rod, *N*, of which the lower extremity is connected with the discharge-gate of the diffuser in such manner that by turning the rods *B B* in one direction or the other their screws 55 *F* cause the nut to ascend or descend, and thereby to open or close the gate of the diffuser. These two rods *B B* are geared together at their upper part by a shaft, *G*, and bevel-gears, that they may be operated by a single crank, *d*. 60 On the opposite side of the axis of the diffuser the movable bottom or gate is maintained closed in the following manner: Each rod *C* has on its lower part a screw-thread, *R*, and its lower end is supported in a step-bearing, 65 *S*, cast with the base of the diffuser. The screw-thread *R* is fitted with a nut, *T*, on each side of which are articulated connecting-rods *H H*, connected at their lower ends with a counterpoised loop-catch, *L*. These rods *H* 70 are guided in grooves cast in each side of the step-bearing *S*. This guiding prevents on the one part the nuts *T* from turning, and on the other part it maintains the counterpoised loop-catch *L* against the diffuser. A small rod, *W*, 75 which is articulated upon the fixed part forming the step-bearing, and which carries at its upper end a small slide, limits at a certain moment the vertically-descending course of the catch *L*, and after this moment makes it describe an arc of a circle about the lower axis 80 of the said small rod and disengages this catch from the hook *K*, riveted to the gate, which from that time becomes free and may be opened. The two rods *C* are also geared together at 85 their upper parts by a shaft, *G'*, and bevel-gears operated by a single hand-crank, *D**. To open the apparatus at the moment when it is desired to effect the discharge, it is sufficient to turn the crank *D**, which operates the 90 rods *C*, in order to cause the descent of the rods *H* and afterward of the catches *L*. When by the movement of descent the pivots on the ears of the catches have arrived at the bottoms of slots in the small suspended rods *W*, the 95 catches describe the arc of a circle until they liberate themselves from the hooks *K*. The movable bottom then opens freely under the influence of the weight of the charge of the diffuser, combined with the movement of the rods 100

B, which control the descent. After having emptied the apparatus, the rods B are turned in a reverse direction by means of the crank-handle D, and the bottom is returned by the action of counterpoise A, combined with that of the closing-rods, to occupy the closing position. The gate is then secured at two points. The fastening-rods C, being then turned by the crank D*, draw up the rods H, and the counterbalanced loop-catches L return automatically under the hooks K, owing to their weight. Nothing more now remains to be done but to screw up all the rods B B C C hard to effect a tight closing of the gate and put the apparatus in condition to receive a new charge. The gate is thus held at four points, and is consequently well sustained to preserve a tight joint.

It will be understood that by means of these devices the entire operation is effected from above the apparatus without loss of time and without necessitating any manual work for emptying the diffuser.

What I claim as my invention, and desire to secure by Letters Patent, is—

25 1. The combination, with the diffusing-vessel having a counterbalanced bottom or dis-

charge-gate, of the screw-rods B B, the nuts J J on the said rods, the fixed slideways M M for said nuts, the rods N N, connecting said nuts with the bottom or gate, and the shaft G, geared with the upper ends of said screw-rods to enable both to be operated simultaneously for opening and closing the gate from above the apparatus, substantially as herein described.

2. The combination, with the diffusing-vessel having a counterbalanced bottom or discharge-gate, of the screw-rods C C, nuts T T, rods H H, counterbalanced catches L L, hooks K K, and rods W W, and the shaft G', geared with the upper ends of said screw-rods to enable both to be operated simultaneously for locking and unlocking the bottom or gate from above the diffusing apparatus, substantially as and for the purpose herein set forth.

In testimony whereof I have signed this specification in the presence of two subscribing witnesses.

MARTIN LÉONARD EDMOND DUVAL.
